(57) **CLAIM**

The ornamental design for a multi-functional pen holder assembly, as shown and described.

DESCRIPTION

FIG. 1 is a perspective view of a multi-functional pen holder assembly;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective back view thereof;

FIG. 9 is a perspective front view thereof; and,

FIG. 10 is a perspective front view thereof.

The various items shown in broken lines are included for the purpose of ease of illustration and form no part of the claimed design.
